UNITED STATES PATENT OFFICE.

ALBA C. BOOTH, OF BURLINGTON, VERMONT, ASSIGNOR OF ONE-FOURTH TO FREDERICK M. COON, OF BURLINGTON, VERMONT.

BOTTLE CAP.

Application filed January 16, 1926. Serial No. 81,789.

This invention relates to improvements in bottle closures, with which a crimped cap is usually employed, the invention having for its object, the provision of a structure to permit the bottle to be opened and the contents discharged without removing the crimped cap from the mouth of the bottle.

More specifically stated, the invention comprehends the use of a crimped cap having an opening in the top thereof, and between which cap and an apertured washer, is clamped a disk of suitable material to permit of its being severed or otherwise destroyed, to remove that portion of the disk lying between the openings of the cap and washer, with a view of providing an unobstructed passage for the discharge of the contents of the bottle, the openings in the cap and washer being of substantially the same diameter as the interior diameter of the neck of the bottle for this purpose.

With the above and other objects in view, the invention further includes the following novel features and details of construction, to be hereinafter more fully described, illustrated in the accompanying drawing and pointed out in the appended claim.

In the drawing:—

Figure 1 is a top plan view of a bottle showing my present invention applied thereto.

Figure 2 is a sectional view taken on line 2—2 of Figure 1.

Referring to the drawing in detail, where-in like characters of reference denote corresponding parts, the reference character 10 indicates a bottle having a neck 11 with the conventional form of bead 12 extending around the periphery thereof, all of the above being of the usual and well known construction and forming no part of the present application for Letters Patent but being merely shown for purposes of illustration in bringing forward the novel advantages of the above entitled invention.

In carrying out my invention I provide the conventional form of bottle cap 13 secured in the usual manner to the bead 12 provided upon the neck. Said cap in addition includes an opening 14 registering with the bore or passage way in the neck 11 of the bottle 10. A disk 16 is positioned upon

the under side of the bottle cap 13 and exposed to the opening 14 in the cap and having its under side and marginal edges resting upon the upper side of an annular packing ring in the form of a cork gasket 15 which engages the periphery of the bottle neck 11. Said disk 16 is formed of some destructible material, and in this instance of celluloid, whereby the latter may be readily and easily punched or broken in withdrawing or extracting the contents of the bottle 10.

It will thus be noted from the foregoing description and accompanying drawing, that this invention provides an exceedingly useful and advantageous bottle cap which owing to the construction thereof may be manufactured at a very low cost and consequently be used upon all types and forms of bottles. The disk is interposed to permit destruction, being preferably formed of celluloid, whereby any suitable instrument utilized in either punching or cutting out the disk consequently obviates the necessity of using a bottle opener which usually chips the bead 12 formed upon the neck 11 of the bottle 10 much to the discomfort of the user.

The invention is susceptible of various changes in its form, proportions and minor details of construction, and the right is herein reserved to make such changes as properly fall within the scope of the appended claim.

Having described my invention what is claimed is:—

A bottle closure comprising a washer adapted to repose upon the mouth of the bottle and having a central opening, a crimped cap adapted to embrace the neck of the bottle and having a central opening co-extensive with the opening in said washer, a disk of readily destructible material interposed between the cap and washer and clamped therebetween, and adapted to have its entire area equivalent to the size of the opening in the cap to be removed to provide an unobstructed passage for the contents of the bottle, and said openings in the cap and washer having diameters equal to the interior diameter of the neck of the bottle.

In testimony whereof I affix my signature.

ALBA C. BOOTH.
